CLAIM

The ornamental design for a combined air purifier and cleaner, as shown.

DESCRIPTION

FIG. 1 is a top and side perspective view of a combined air purifier and cleaner showing my new design;

FIG. 2 is a side perspective view thereof;

FIG. 3 is a side perspective view thereof of the side opposite that shown in FIG. 2, with the rear flat foot element moved 90° toward the rear;

FIG. 4 is a front elevational view thereof;

FIG. 5 is a rear elevational view thereof;

FIG. 6 is a top plan view thereof with the feet positioned closer to the front; and,

FIG. 7 is a bottom plan view thereof.
